UNITED STATES PATENT OFFICE.

FRANK McINTYRE, OF NEW YORK, N. Y., ASSIGNOR TO EAGLE PENCIL COMPANY, OF NEW YORK, N. Y.

DESIGN FOR A DISPLAY-BOX FOR PENHOLDERS AND PENCILS.

No. 39,437.

Specification for Design.

Patented Aug. 4, 1908.

Application filed April 24, 1908. Serial No. 429,106. Term of patent 7 years.

To all whom it may concern:

Be it known that I, FRANK McINTYRE, a citizen of the United States, residing at New York, county and State of New York, have invented a new, original, and ornamental Design for a Display-Box for Penholders and Pencils, of which the following is a specification, reference being had to the accompanying drawing, forming part thereof.

Figure 1 is a perspective view of the display box, and Fig. 2 is a front elevation of the same.

The design, as shown, consists of a display box having a semi-tubular body, simulating

a tunnel, supported upon a rectangular base having outwardly and downwardly flaring sides. The floor and roof of the semi-tubular tunnel-like body are perforated with a series of holes designed to receive and hold the pencils, penholders, etc. to be displayed.

I claim—

The ornamental design for display box for penholders and pencils, as shown.

FRANK McINTYRE.
